RADIO MONITORING SYSTEM

Walter van B. Roberts, Princeton, N. J., assignor
to Radio Corporation of America, a corpora-
tion of Delaware

Application March 14, 1942, Serial No. 434,683

6 Claims. (Cl. 250—20)

My present invention relates to radio signalling systems, and more particularly to a radio receiving system including monitor devices.

To be useful a television system should include means for calling attention to unscheduled television transmissions. This is true because a large part of the interest in television may, in the future, reside in telecasting of news events which by their unexpected nature are likely to occur at times when no program is scheduled. To some extent the same is true of sound broadcasting. However, in the latter case the broadcasting transmitter is usually on the air, but the receiver may not be turned on or tuned to the station that has some announcement of importance to make. In the case of facsimile transmission, the transmitted information is not lost if the receiver is arranged to run all the time. However, in the case of facsimile transmission, the material may be unnoticed at the facsimile receiver for some time.

In accordance with the present invention a combination facsimile receiver and alarm system is provided which is adapted to monitor all the aforesaid services so that important material may be called to the attention of the householder without delay.

An important object of the present invention is to provide a receiving system wherein the detecting network is continually operative, there being provided a relay device for energizing the rest of the receiver solely while a carrier is being received.

Another important object of the invention is to provide in a signalling system, a method of transmitting on a carrier one type of modulation which is representative of facsimile signals, and another type of modulation which is representative of an alarm signal, and in the case of the latter type of modulation there being utilized a low percentage amplitude modulation.

Another object of the invention is to provide a receiving system for frequency modulated carrier wave energy wherein flat frequency response transformers are utilized prior to the demodulator input circuit so that amplitude modulation effects will not be produced at the said input circuit whereby an amplitude modulation alarm signal may be placed on the carrier at specified times, and such alarm signal being derived from the aforesaid demodulator.

Still another object of the invention is to provide a novel and improved type of vibrating magnetic selective coupling device in an alarm system of a radio receiver, the magnetic coupling

being purely motionless and transmitting special modulation tones.

The novel features which I believe to be characteristic of my invention are set forth in particularity in the appended claims; the invention itself, however, as to both its organization and method of operation will best be understood by reference to the following description taken in connection with the drawing in which I have indicated diagrammatically a circuit organization whereby my invention may be carried into effect.

Referring to the accompanying drawing, there is shown a receiving system that can be used in connection with the present invention. As stated heretofore, the receiver is a combination facsimile receiver and alarm system wherein important matter may be called to the attention of the householder at such times when it is desired to transmit unscheduled or unexpected material. For the sake of simplicity of illustration, certain networks of the receiving system are shown in schematic form. Let it be assumed that the facsimile signals are applied to the carrier at the transmitter by frequency modulation. In other words, the carrier at the transmitter has a substantially constant amplitude, and the facsimile signals are utilized to vary the carrier frequency in a manner well known to those skilled in the art of frequency modulation.

Merely by way of example, the carrier may be in the ultra-short wave range, such as 70 megacycles (mc.). Of course, the invention is in no way limited to that carrier frequency value, since frequencies below that band may be employed. The alarm signals are to be understood as applied in the form of amplitude modulation to the carrier. In other words, the carrier amplitude will be varied at the particular modulation tone, or tones, representative of different types of alarm signals which may be utilized. Those skilled in the art of radio communication are fully aware of the particular manner in modulating a carrier with one type of modulation such as frequency modulation, and at the same time modulating the same carrier with another type of modulation such as amplitude modulation.

At the receiver the radiated modulated carrier energy is collected at an antenna A, and the latter may be of any desired type. There are shown at least two stages of radio frequency amplification, and each stage being provided with tuned input and output circuits. Each of the transformers T, T₁ and T₂ has its primary and secondary circuits each tuned to the incoming carrier frequency. In

this way sufficient selectivity is provided for the detector, or demodulator, which is represented as of the diode type. The detector load resistor 1 develops amplitude modulation signal components which are applied to the carrier in the form of alarm signals. An AVC (automatic volume control) circuit is shown connected to the cascaded radio frequency amplifiers so as to maintain a substantially constant carrier amplitude at the input circuit of the demodulator.

The tubes of the cascaded radio frequency amplifiers and the detector diode are kept energized continually from a preferably special power source. It will be understood that the filaments, or heater elements, of these various tubes are connected to said special power supply source. The plate circuits of the radio frequency amplifiers are shown connected to a plate energizing connection 2. The symbol +B designates such a positive potential source. The electromagnetic relay 3 is included in circuit with the plate supply voltage connections to the radio frequency amplifiers. With modern low current tubes used in the stages up to, and including, the detector much power is not required, and the tubes have long life. When no signals are coming in there is little, or no, AVC voltage developed across resistor 1. The plate current flowing through connections 2 and the winding of relay 3 are normal, and hold the pivoted contact, or armature, element 4 away from the contact point 5. A spring is provided to pull armature 4 away from the electromagnetic relay 3, thereby closing switch 4-5, when the AVC action causes the plate current flow through the relay winding to decrease to a low value.

The switch 4-5 is shown inserted in series with the primary winding of a power supply transformer 6. The secondary winding of the transformer is connected to the usual power rectifier 7. The filtered rectified power supply voltage is fed to the plates of all tubes which follow the demodulator of the system. An auxiliary secondary winding is provided on the power supply transformer 6, and is adapted to connect to the heater elements, or filaments, of all of the tubes following the demodulator. This is purely illustrative. It will be understood that switch 4-5 could be in the secondary circuit of transformer 6. Further, the power for the demodulator and prior stages could come from the source supplying transformer 6.

When a modulated carrier is collected by antenna A, AVC bias is developed across resistor 1 with the result that the current flowing through the winding of relay 3 decreases. This results in closure of switch 4-4, and all the tubes following the diode detector are immediately energized. There are two main channels which follow the diode detector. One of these is a facsimile receiver, while the other is a group of selectively operated alarm bells, or other indicator devices. In the present example, facsimile signals are derived from the frequency modulation of the carrier, while the alarm signals are derived from the amplitude modulation of the same carrier. Of course, these two modulations might be interchanged.

Considering first the frequency modulation (FM) portion of the system, it will be understood that a limiter network, designated by the numeral 8, is employed. This limiter functions to wipe out any amplitude modulation (AM) effects of the modulated carrier wave prior to impression of the modulated carrier energy on the discriminator-rectifier 9. Adjacent to the rectangle des-

ignated "AM Limiter" there is shown in purely pictorial manner the limiter input-output characteristics. Those skilled in the art are fully acquainted with this characteristic, as well as with the usual S-shaped characteristic of the discriminator-rectifier 9. There will be fed to the network 9 modulated carrier energy which is variable solely in frequency. The limiter network 8 will remove any of the amplitude modulation tones which are representative of the alarm signals. The output of the network 9 will be the facsimile modulation signals. The numeral 10 denotes a facsimile recorder device of any well known and desired construction. The manner of constructing a facsimile recorder is too well known in the art to require description. It is to be understood that any well known type of recorder may be used.

Considering now the second channel of the receiving system, it will be understood that the modulation voltage developed across the diode load resistor 1, which is by-passed by the carrier by-pass condenser 1', will be representative solely of the AM signals which were applied to the carrier at the transmitter. By way of example, there is shown herein the case wherein a modulation tone A, and a different modulation tone B, have been applied to the carrier. Of course, a single modulation tone may be utilized, or more than two tones may be employed. A coupling condenser 11, which passes the modulation tone frequencies, connects the anode end of resistor 1 to the input terminals of the modulation tone amplifiers 12 and 12'. There will be described in detail the construction of the circuits between the amplifier 12 and the indicator device. It will be understood that the same construction is employed in the case of the circuits following the modulation amplifier 12'.

Since each of amplifiers 12 and 12' is fed with combined modulation tones, there must be provided a frequency selective device to separate for each indicator its respective modulation tone. There is shown employed a vibratory reed 13 having one end fixedly secured to a support. The free end of the reed is provided with a magnet 14. One pole of the magnet is located adjacent a driving coil 15. One end of the driving coil is grounded while its opposite end is coupled by condenser 16 to the upper end of the plate voltage feed coil 17 of amplifier 12. As explained previously, the plate feed coil 17 is included in the power supply circuit following power rectifier 7.

The opposite pole of magnet 14 is located adjacent a coil 18, one end of which is connected to the anode of a diode rectifier 19. The opposite end of coil 18 is connected to the cathode of diode 19 through the winding of electromagnet 20. The winding of electromagnet 20 is bypassed for the modulation tone frequency. The electromagnet 20 is arranged to actuate a normally-open switch device 21. The switch device 21 is arranged in circuit with any desired type of indicator device, such as a bell, lamp, or buzzer.

To explain the operation of the alarm portion of the system, it will be understood that the amplified modulation tones in each case drive a mechanically tuned vibrating reed 13, and that each reed carries a permanent magnet upon which the modulation tone current acts. When the modulation tone frequency is equal to that of its respective vibrator, the motion of the latter induces a current in its respective coil 18. The induced current is rectified by diode 19 thereby causing switch 21 to close. Such vibrating

reed devices are cheap and easy to make; they are reliable in operation and are readily made extremely selective. It will now be seen that the coupling between coils 15 and 18 is purely motional.

Let us assume that the vibrator reed associated with amplifier 12 is tuned to 100 cycles, and that when the transmitting station has been informed that an unscheduled television transmission is taking place an amplitude modulation of 100 cycles is impressed on the carrier. This causes switch 21 to be closed. As a result a bell, or a buzzer, is energized for so long as the modulation tone of 100 cycles is applied to the carrier. Of course, the modulation tone may be continuous, or repeated at intervals at the discretion of the transmitter. At the same time the facsimile material applied to the carrier is interrupted to insert a description of what the alarm bell was rung for. If the transmitter carrier had not been on when the alarm was to be given the procedure would have been the same, except that a few seconds would have to be allowed for tube 12 to heat up.

In case the householder does not also own a television receiver, he would probably not care for the television service described above. He might, however, like to be informed that something important was being announced over the sound radio stations. In that case he would have his facsimile receiver equipped with a relay tuned to say 90 cycles, so that his bell would ring only on 90 cycle modulation. The latter would be used by the transmitter when, for example, an address of national importance to all the people was to be put on the air at an unscheduled time.

As stated heretofore, the present receiving system is not limited to a single service. Tube 12', which is in parallel with the input terminals of amplifier 12, will lead to a similar alarm circuit except for the modulation tone frequency to be employed. The bells, or other indicators, associated with the parallel alarm circuits should preferably be aurally distinguishable. In a simplified embodiment the outputs of tubes 12 and 12' could actuate tuned vibrator reeds which would strike directly on different bells thus providing differentiation both by the tones of the bells and by the frequency of the clapper blows. It is, furthermore, possible to code the information given by the operation of the relays. For example, one relay circuit may be arranged to strike a rich-toned bell on the hour to act like a clock. This same bell, if rung continuously, would constitute a call to come to the facsimile recorder, and read what it says is going on. As another example, a code of ringing would give notice that the recorder had just printed a weather report, or a war news bulletin, indicating by the ringing code which it is.

It is to be clearly understood that the nature of the modulated carrier wave is purely illustrative. For example, there could be employed a carrier which is amplitude modulated by a sub-carrier, while the sub-carrier is frequently modulated by the facsimile modulation signals. Such type of modulated wave has been used in facsimile transmission. In such case, the main carrier would be amplitude modulated by the modulation tones representative of the alarm signals. In this type of modulated wave, it is only necessary to subject the main carrier to amplitude modulation to secure the frequency modulated subcarrier, and the latter would then

be subjected to the frequency modulation detection as described in this application.

Each of transformers T, T₁ and T₂ desirably has a flat frequency response characteristic so that undesired amplitude modulation components will not be developed. Such components are produced on the frequency modulated carrier due to round-peaked response curves. Furthermore, it is desirable that the modulation tones be applied in the form of low percentage amplitude modulation.

While I have indicated and described a system for carrying my invention into effect, it will be apparent to one skilled in the art that my invention is by no means limited to the particular organization shown and described, but that many modifications may be made without departing from the scope of my invention, as set forth in the appended claims.

What I claim is:

1. In a radio signalling system, a receiver comprising a modulated carrier wave amplifier followed by a demodulator, means for continuously energizing said amplifier and demodulator, means for applying to said amplifier modulated carrier waves whose modulation includes modulation signals of two different types, a network coupled to the amplifier output for utilizing modulation of one type, a second network coupled to the demodulator output for utilizing the modulation of the second type, a power supply circuit for energizing both said networks, and means, responsive to carrier-derived energy, for rendering said power supply circuit operative to energize both said networks.

2. In a radio signalling system, a receiver comprising a modulated carrier wave amplifier followed by a demodulator, means for applying to said amplifier modulated carrier waves whose modulation includes modulation signals of two different types, a network for utilizing modulation of one type, a second network for utilizing the modulation of the second type, a power supply circuit for both said networks, and means, responsive to carrier-derived voltage, for rendering said power supply circuit operative to energize both said networks, one of said modulations being applied to the carrier in the form of frequency modulation, and the other type of modulation being applied to the carrier in the form of amplitude modulation.

3. In a radio signalling system, a receiver comprising a modulated carrier wave amplifier followed by a demodulator, means adapted to continuously energize said amplifier and demodulator, means for applying to said amplifier modulated carrier waves whose modulation includes modulation signals of two different types, a network for utilizing modulation of one type, a second network for utilizing the modulation of the second type, a power supply circuit for both said networks, and means, responsive to carrier-derived energy, for rendering said power supply circuit operative to energize both said networks, said second network including an indicator device, and a vibratory magnetic device selectively coupling said indicator to the output of said demodulator.

4. In a radio signalling system, a receiver comprising a modulated carrier wave amplifier followed by a demodulator, means for applying to said amplifier frequency modulated carrier waves which are amplitude modulated by a tone frequency, a network coupled to the amplifier for utilizing the frequency modulation, a second net-

work coupled to the demodulator for utilizing the tone voltage output of the latter, a power supply circuit for both said networks, and means, responsive to carrier-derived current, for rendering said power supply circuit operative to energize both said networks.

5. In combination, a modulated carrier wave transmission network including a demodulator, said network being conditioned for wave reception, means for applying to said network frequency modulated carrier waves whose carrier is amplitude modulated by at least one modulation frequency, limiter means coupled to said network in parallel with said demodulator and at a point prior to the demodulator input for removing the amplitude modulation from the modulated wave, means detecting the limited wave energy, means utilizing the detected energy, means coupled to the demodulator output for providing voltage of said one modulation frequency, means for utilizing said voltage and additional means, responsive solely to reception of waves by said network, for rendering said limiter means, detecting means and said demodulator output means operative.

6. In combination, a modulated carrier wave transmission network, including a demodulator, means for applying to said network frequency modulated carrier waves whose carrier is amplitude modulated by at least one modulation frequency, limiter means coupled to said network in parallel with said demodulator and at a point prior to the demodulator input for removing the amplitude modulation from the modulated wave, means detecting the limited wave energy, means utilizing the detected energy, means coupled to the demodulator output for providing voltage of said one modulation frequency and means for utilizing said voltage, said network and demodulator being in a state of continuous energization, a normally inoperative power supply system for the limiter means, detecting means and said mean coupled to the demodulator output, and means responsive to the reception of a modulated carrier wave for rendering the power system operative.

WALTER VAN B. ROBERTS.
